DESIGN FOR A BLIND FOR BRIDLES

Jesse D. Padgitt, Dallas, Tex.

Application September 15, 1944, Serial No. 115,307

Term of patent 14 years

(Cl. D38—6)

To all whom it may concern:

Be it known that I, Jesse D. Padgitt, a citizen of the United States and a resident of Dallas, in the county of Dallas and State of Texas, have invented a new, original, and ornamental Design for Blind for Bridles, of which the following is a specification.

Reference is had to the accompanying drawing, forming part thereof, in which:

Fig. 1 is a front view in elevation of a blind for bridles showing my new design.

Fig. 2 is a rear view of the blind.

Fig. 3 is an end view of the same.

Fig. 4 is a fragmentary enlarged section of the design.

I claim:

The ornamental design for a blind for bridles, as shown.

JESSE DAVID PADGITT.
